UNITED STATES PATENT OFFICE

HORACE F. GRUMAN, OF ST. LOUIS, MISSOURI, ASSIGNOR TO LEWIS INVISIBLE-STITCH MACHINE COMPANY, OF KITTERY, MAINE, A CORPORATION OF MAINE

SEWING MACHINE

Application filed May 3, 1928. Serial No. 274,834.

This invention relates to new and useful improvements in sewing machines especially adapted for joining two body fabrics by a French seam, and embodies certain improvements over my co-pending application Serial No. 238,793, filed Dec. 9, 1927.

Among the several objects of my invention are to improve the work presenting mechanism of the second or rear seam forming mechanism, and to provide such a mechanism which is simple in construction and is positive in operation.

With these and other objects in view which will more fully appear, the nature of the invention will be more clearly understood by following the description, the appended claims, and the several views illustrated in the accompanying drawings.

In the drawings:—

20 Figure 1 is a perspective view showing both the front and rear seam forming mechanisms of my invention, the horizontal presser foot and associated parts being separated to better disclose the mechanism thereunder,

25 Figure 2 is a vertical transverse sectional view taken through my machine and taken on the line 2—2 of Figure 1,

30 Figure 3 is a perspective view of the feed rocker for imparting back and forth movements to the horizontal feed dog, the view also showing a rocker for imparting back and forth movements to the front vertical feed dog,

35 Figure 4 is a perspective view similar to Figure 1 but illustrating another embodiment of my invention,

Figure 5 is a perspective view illustrating the steps performed by my invention in joining two fabrics by a French seam,

40 Figure 6 is a detail view of the ridge forming finger, and

Figure 7 is a perspective view of the French seam formed by my invention.

Like reference numerals designate corresponding parts throughout the several figures of the drawings.

In the accompanying drawings, I have disclosed only enough of a sewing machine as is necessary for a clear understanding of my invention. The machine is of the flat

bed type and includes a base 5, and journaled in a suitable bearing on this base is a rotary shaft 6.

The first seam forming mechanism

The front seam forming mechanism includes a stitch forming mechanism and a cooperating work presenting mechanism, both of which are substantially identical with those shown in my co-pending application referred to above. Briefly stated, the stitch forming mechanism includes a straight needle 7 which is reciprocatory in a horizontal plane across the line of feed, and a co-operating 4-motion threaded looper 8 for forming a line of Grover & Baker stitches. The needle 7 is attached to a needle bar 9. The specific means for operating the looper 8 need not be described as the same is fully described and illustrated in my co-pending application referred to above.

The work presenting mechanism includes a vertical needle plate or guide 10, a vertical 4-motion feed dog 11 which operates through an opening in said plate, and a vertical presser foot 12 which cooperates with the plate 10 and dog 11 to feed downwardly extending marginal portions *a* and *b* of the body fabrics A and B rearwardly past said stitch forming mechanism so as to join said portions by a line of stitches *c*. This stitch forming mechanism, and also this work presenting mechanism, is disposed entirely below the general plane containing the body fabrics A and B.

The trimming mechanism

Cooperating with the lower face of the needle plate 10 is a trimmer blade 13 which oscillates in a horizontal plane below the line of stitches *c* to trim the edges of the downturned marginal portions *a* and *b* of the body fabrics. The blade 13 is secured to a vertically disposed rock shaft 14 which is oscillated by any suitable mechanism. This trimming mechanism is substantially identical with that disclosed in my co-pending application referred to above and therefore a further description thereof is thought to be unnecessary.

The second seam forming mechanism.

The second seam forming mechanism is disposed in rear of the first seam forming mechanism and includes an upper stitch forming mechanism which is entirely disposed above the general plane of the body fabrics, and a cooperating upper work presenting mechanism.

The upper stitch forming mechanism is the same as is disclosed in my co-pending application and includes a reciprocatory needle 15 which is fulcrumed directly above the seam for oscillations in a plane transverse to the line of feed. Located in rear of the trimmer 10 is a vertically reciprocatory ridge forming device or finger 16 which projects the seamed fabrics including the formed seam upwardly into a ridge formation whereby the upper work presenting mechanism will engage said ridge and feed the same rearwardly past the rear stitch forming mechanism. Disposed in rear of the trimming mechanism and located in a plane above the general plane of the body fabrics is a stationary presser foot 17 which is provided on its under face with a guide groove or channel 18 which receives the ridge *d* as it is formed by the ridge forming finger 16. This groove 18 is formed in a boss 19 which extends upwardly from the presser foot or plate 17 and includes spaced vertical walls 20-21 and a top wall 22. The wall 21 and the top 22 are cut away intermediate the front and rear ends, and the rear or exposed portion of the wall 20 constitutes a vertical needle or guide plate 20^a. Supported on the stationary presser foot or plate 17 is a vertical foot 23 which cooperates with the vertical needle plate 20^a to clamp the ridge *d* of fabrics therebetween 25. A vertical 4-motion feed dog 24 projects through an opening in the needle plate 20^a for cooperation with the vertical presser foot 23 to feed the ridge *d* of the fabrics past the upper and rear stitch forming mechanisms, the needle 15 passing through suitable aligned openings formed in the presser foot 23, the needle plate 20^a, and vertical feed dog 24. The means for imparting four motions to the vertical feed dog 24 are fully described in my co-pending application.

Cooperating with the presser foot to feed the body fabrics rearwardly is a horizontal 4-motion feed dog 25 which includes a plurality of spaced feed sections 25^a. This feed dog is fixedly mounted on a feed bar 26 having its rear end pivoted as at 27 to the upper end of the feed rocker 28, said rocker being pivotally mounted at its lower end as at 29 to the base 5. A link 30 has one end pivotally connected to the feed rocker 28 and the other end engaged with the eccentric fixed on the shaft 6. Thus upon rotation of the shaft 6 the feed rocker will impart backward and forward movement to the horizontal feed

dog. In order to move the feed dog up and down, I have fixed an eccentric 31 on the shaft 6 and cooperating with the eccentric is a slide 32 which is slidably mounted in an opening 33 formed in a block 34 which is pivoted to the feed rocker 28 by the upper pivot 27 thereof. It will thus be seen that when the shaft 6 is rotated the eccentric 31 will raise the block 34 up and down and said block will also swing about the pivot 27. Disposed between the block 34 and the feed bar 26 is a coil spring 35 which tends to yieldably compress the fabrics against the horizontal foot when the block 34 is raised.

Disposed below the horizontal presser foot 17 is a vertically reciprocatory work clamp 36 which cooperates with said foot to clamp the fabrics against the thrust of the upper needle 15 during successive idle movements of the feed. This work clamp is fixed to the upper end of a vertically disposed support 37 which is mounted for reciprocations in suitable guides mounted on the base 5. Disposed between the base 5 and the support 37 is a spring 38 which functions to yieldably retain the work clamp 36 in cooperative clamping relation with the horizontal presser foot 17. It is desirable to positively lower the work clamp 36 during each feeding movement of the feed dog 25 and for this purpose, I have provided a lever 39 which is fulcrumed intermediate its ends as at 40 between the support 37 and the block 34. The rear end of the lever 39 engages a shoulder 41 formed on the block 34 and the forward end of the lever engages on a shoulder 42 formed on the support 37. Consequently when the block 34 is raised by the eccentric 31, the rear end of the lever 39 will also be raised and this will move the front end of the lever downwardly and thereby depress the support 37 against the tension of the spring 38, thereby moving the work clamp downwardly and out of cooperative clamping relation with the horizontal presser foot 17.

The ridge forming element or finger 16 is fixed to the front end of a lever 43 which extends longitudinally of the feed bar 26 and is pivotally connected as at 44 by a transverse pivot to a depending ear 45 integral with the feed bar. The finger 16 projects upwardly through an opening 46 formed in the central feed section 25^a and also through an opening formed in the work clamp 36, and the feed sections 25^a operate through slots 47 formed in the work clamp 36.

The rear end of the lever 43 is formed with a cam slot 48 whose major axis is normally inclined upwardly and rearwardly. A stationary pin 49 fixed to the base 5 in any suitable manner, is disposed in the slot 48. Thus when the feed bar 26 is raised and lowered, the pivot 44 will be correspondingly moved and consequently the lever 43 will swing about the

pin 49 and thereby raise and lower the ridge forming finger 16. The movement of the finger 16 will be considerably increased or multiplied over the up and down movement of the feed bar, by reason of the lever being pivoted on the feed bar and having the pin and cam slot connection 48, 49. As a result, the upper needle 15 will pass through the inner marginal portions *e* and *f* below the trimmed edges of the outer marginal portions *a* and *b* to thereby join the inner marginal portions by a line of stitches *g* as shown in Figure 7.

In Figure 4, I have shown a slightly modified form of means for supporting and operating the ridge-forming finger 16. The finger 16 is fixed to a rock arm 50 which is rigidly connected to a rock shaft 51 journaled in bearings 52, 52 mounted on the base 5. An actuating rock arm 53 is fixed to the rock shaft 51 and extends in a direction opposite the rock arm 50. An eccentric 54 is fixed on the rotary shaft 6 and the arm 53 is retained in constant engagement with the eccentric by a spring 55. It will be observed that the finger 16 is not supported on the feed bar, but that the rock arms 50, 53 and rock shaft 51 constitute a lever which is fulcrumed on an axis transverse to the line of feed, that the finger is mounted on one end of the lever, and that means cooperate with the other end of the lever for rocking the same to reciprocate the finger vertically.

From the foregoing, it will be observed that the body fabrics A and B are normally disposed in a horizontal plane and at the beginning of the operation the adjacent marginal edge portions *a* and *b* are turned downwardly into side by side relation and fed rearwardly past the needle 7 of the front stitch forming mechanism. After the stitches *c* have thus been formed the lower edges of the marginal portions *a* and *b* are trimmed by the trimmer 13. Immediately following the trimming operation the body fabrics together with the previously formed and trimmed seam are projected upwardly to form the ridge *d*. The ridge *d* is then fed rearwardly by the cooperation of the vertical presser foot 23 and the cooperating vertical feed dog 24 past the rear stitch forming mechanism. During this movement of the fabrics, the body fabrics on opposite sides of the ridge *d* are fed rearwardly through the cooperation of the horizontal presser foot 19 and the horizontal feed dog 26. The work clamp 36 is reciprocated vertically in timed relation with the horizontal feed dog 26 whereby the clamp functions to clamp the body fabrics against the horizontal foot during the non-feeding stroke of the horizontal feed dog and during the penetrating movement of the rear needle, and whereby the clamp will be lowered during the feed stroke of the horizontal feed dog to permit said dog to feed the fabrics a stitch length distance. It will also be observed that

the ridge forming finger is pivoted to move with the horizontal feed dog, and that means are provided for oscillating said finger during each cycle whereby the ridge *d* is constantly being formed during the feeding of the fabrics through the machine.

Having thus described the invention, what is claimed is:

1. In a sewing machine for forming French seams, the combination with front and rear stitch forming mechanisms, one of said mechanisms operating entirely below the general plane of the fabrics to be seamed and the other operating entirely above the general plane of said fabrics, means for directing vertical edge portions of fabrics into position for seaming by the front stitch forming mechanism, a trimming mechanism operating in front of the rear stitch forming mechanism for trimming the edge portions of the seamed fabrics, means located in rear of the trimming mechanism for projecting a ridge of the fabrics including the trimmed seam into position for seaming by the rear stitch forming mechanism with the trimmed edge portions of the first seam within the ridge but out of stitching relation with respect to the second stitch forming mechanism, and a horizontal presser foot and a horizontal feed dog located in rear of the front stitch forming mechanism and respectively disposed above and below the seamed fabrics to feed the same past the projecting means and the rear stitch forming mechanism.

2. In a sewing machine for forming French seams, the combination with front and rear stitch forming mechanisms respectively operating entirely below and entirely above the general plane of the fabrics to be seamed, means for directing downwardly extending edge portions of fabrics into position for seaming by the front stitch forming mechanism, means for projecting a ridge of the fabrics including the formed seam into position for seaming by the rear stitch forming mechanism, and means for directing the ridge of fabrics into position for seaming by the rear stitch forming mechanism comprising a vertical presser foot and a cooperating vertical feed dog respectively disposed on opposite sides of the ridge and cooperating therewith, a horizontal presser foot disposed above the general plane of the fabrics and provided with an opening through which the ridge of fabrics projects, and a horizontal 4-motion feed dog disposed below the general plane of the fabrics and cooperating with the horizontal presser foot.

3. In a sewing machine for forming French seams, the combination with front and rear stitch forming mechanisms, one of said mechanisms operating entirely below the general plane of the fabrics to be seamed and the other operating entirely above the general plane of said fabrics, means for directing

- vertical edge portions of fabrics into position for seaming by the front stitch forming mechanism, a trimming mechanism operating in front of the rear stitch forming mechanism for trimming the edge portions of the seamed fabrics, means located in rear of the trimming mechanism for projecting a ridge of the fabrics including the trimmed seam into position for seaming by the rear stitch forming mechanism with the trimmed edge portions of the first seam within the ridge but out of stitching relation with respect to the second stitch forming mechanism, and a horizontal presser foot and a horizontal feed dog located in rear of the front stitch forming mechanism and respectively disposed above and below the seamed fabrics to feed the same past the projecting means and the rear stitch forming mechanism, said ridge forming means comprising a vertically reciprocating finger supported for bodily movements with the horizontal feed dog.
4. In a sewing machine for forming French seams, the combination with front and rear stitch forming mechanisms, one of said mechanisms operating entirely below the general plane of the fabrics to be seamed and the other operating entirely above the general plane of said fabrics, a vertical presser foot located at one side of the vertical edge portions of the fabrics, a vertical feed dog located at the other side of said vertical edge portions and cooperating with the foot to feed the fabrics past the front stitch forming mechanism, means for projecting a ridge of the fabrics including the formed seam into position for seaming by the rear stitch forming mechanism, and a horizontal presser foot and a horizontal feed dog located in rear of the front stitch forming mechanism and respectively disposed above and below the seamed fabrics to feed the same past the projecting means and the rear stitch forming mechanism, the horizontal foot being provided with a recess for receiving the ridge.
5. In a sewing machine for forming French seams, the combination with front and rear stitch forming mechanisms each including a reciprocating needle, one of said mechanisms operating entirely below the general plane of the fabrics to be seamed and the other operating entirely above the general plane of said fabrics, means for directing vertical edge portions of fabrics into position for seaming by the front stitch forming mechanism, a horizontal presser foot arranged in rear of the front stitch forming mechanism and above the seamed fabrics, a vertically movable work clamp disposed below the seamed fabrics and cooperating with the horizontal presser foot to retain the fabrics against movement during the penetrating stroke of the needle of the rear stitch forming mechanism, a ridge forming element operating through the clamp and foot to project a ridge

- of the seamed fabrics into position to be seamed by the rear stitch forming mechanism, and a horizontal feed dog operating through the clamp and cooperating with the horizontal presser foot to feed the seamed fabrics past the ridge forming element and the rear stitch forming mechanism.
6. In a sewing machine for forming French seams, the combination with front and rear stitch forming mechanisms each including a reciprocating needle, one of said mechanisms operating entirely below the general plane of the fabrics to be seamed and the other operating entirely above the general plane of said fabrics, a vertical presser foot located at one side of the vertical edge portions of the fabrics, a vertical feed dog located at the other side of said vertical edge portions and cooperating with the foot to feed the fabrics past the front stitch forming mechanism, a horizontal presser foot arranged in rear of the front stitch forming mechanism and above the seamed fabrics, a vertically movable work clamp disposed below the seamed fabrics and cooperating with the horizontal presser foot to retain the fabrics against movement during the penetrating stroke of the needle of the rear stitch forming mechanism a ridge forming element operating through the clamp and foot to project a ridge of the seamed fabrics into position to be seamed by the rear stitch forming mechanism, and a feed dog operating through the clamp and cooperating with the horizontal presser foot to feed the seamed fabrics past the ridge forming element and the rear stitch forming mechanism.
7. In a sewing machine for forming French seams, the combination with front and rear stitch forming mechanisms, one of said mechanisms operating entirely below the general plane of the fabrics to be seamed and the other operating entirely above the general plane of said fabrics; and work presenting mechanisms for successively presenting vertical edge portions of fabrics to said stitch forming mechanisms, one only of said work presenting mechanisms including a stationary horizontal presser foot and a cooperating horizontal 4-motion feed dog; and each work presenting mechanism including a vertical presser foot and a cooperating vertical 4-motion feed dog.
8. In a sewing machine for forming French seams, the combination with front and rear stitch forming mechanisms, one of said mechanisms operating entirely below the general plane of the fabrics to be seamed and the other operating entirely above the general plane of said fabrics, and work presenting mechanisms for successively presenting vertical edge portions of fabrics to said stitch forming mechanisms, one of said work presenting mechanisms including a stationary

- senting mechanisms for successively presenting vertical edge portions of fabrics to said stitch forming mechanisms, one of said work presenting mechanisms including a stationary horizontal presser foot and a cooperating horizontal 4-motion feed dog, means for imparting back and forth movements to said dog including a rotary shaft, a feed rocker actuated from said shaft, and a feed bar pivotally connected to the rocker and supporting the feed dog, and means for imparting up and down movements to the feed dog comprising a frame pivoted to the feed rocker and extending under the feed bar, a spring interposed between the frame and the feed bar, a block slidably mounted in the frame, and an eccentric fixed to the shaft and engaging the block to slide the latter relative to the frame.

15 15. In a sewing machine for forming French seams, the combination with front and rear stitch forming mechanisms, one of said mechanisms operating entirely below the general plane of the fabrics to be seamed and the other operating entirely above the general plane of said fabrics; and front and rear work presenting mechanisms for successively presenting vertical edge portions of fabrics to said stitch forming mechanisms, the rear work presenting mechanism including a stationary horizontal presser foot and a cooperating horizontal 4-motion feed dog, and each work presenting mechanism including a vertical presser foot and a cooperating vertical 4-motion feed dog, means for imparting back and forth movements to the horizontal feed dog and to the vertical feed dog of the front work presenting mechanism including a rotary shaft, a feed rocker actuated from said shaft, and feed bars pivotally connected to the rocker and respectively supporting the horizontal feed dog and the front vertical feed dog, and means for imparting up and down movements to the horizontal feed dog and lateral reciprocatory movements to said front vertical feed dog.

20 16. In a sewing machine for forming French seams, the combination with front and rear stitch forming mechanisms, one of said mechanisms operating entirely below the general plane of the fabrics to be seamed and the other operating entirely above the general plane of said fabrics; and front and rear work presenting mechanisms for successively presenting vertical edge portions of fabrics to said stitch forming mechanisms, the rear work presenting mechanism including a stationary horizontal presser foot and a cooperating horizontal 4-motion feed dog, and each work presenting mechanism including a vertical presser foot and a cooperating vertical 4-motion feed dog, means for imparting back and forth movements to the horizontal feed dog and to the vertical feed dog of the front work presenting mechanism including a rotary shaft, a feed rocker actuated from said shaft, and feed bars pivotally connected to the rocker and respectively supporting the horizontal feed dog and the front vertical feed dog, and means for imparting up and down movements to the horizontal feed dog comprising a frame pivoted to the feed rocker and extending under the feed bar to which the horizontal feed dog is connected, a spring interposed between the frame and the last mentioned feed bar, a block slidably mounted in the frame, and an eccentric fixed to the shaft and engaging the block to slide the latter relative to the frame.

25 17. In a sewing machine, a work presenting mechanism including a horizontal 4-motion feed dog, and a vertically reciprocating ridge forming element supported for bodily movements therewith.

30 18. In a sewing machine, a work presenting mechanism including a horizontal 4-motion feed dog, a feed bar supporting said dog, and a vertically reciprocating ridge forming element fulcrumed on the bar for bodily movements therewith.

35 19. In a sewing machine, a work presenting mechanism including a horizontal 4-motion feed dog, a feed bar supporting said dog, means for imparting up and down and backward and forward movements to the bar, a lever extending longitudinally of the feed bar and fulcrumed intermediate its ends thereon, a ridge forming element fixedly connected to one end of the lever, and means cooperating with the other end of said lever for vertically reciprocating the ridge forming element during the up and down movements of the feed bar.

40 20. In a sewing machine, a work presenting mechanism including a horizontal 4-motion feed dog, a feed bar supporting said dog, means for imparting up and down and backward and forward movements to the bar, a lever extending longitudinally of the feed bar and fulcrumed intermediate its ends thereon, a ridge forming element fixedly connected to one end of the lever, and means cooperating with the other end of said lever for vertically reciprocating the ridge forming element during the up and down movements of the feed bar, said means comprising a cam slot formed in the end of the lever, and a stationary pin cooperating with said cam slot.

45 21. In a sewing machine, a work presenting mechanism including a horizontal 4-motion feed dog, a feed bar supporting said dog, means for imparting up and down and backward and forward movements to the bar, a ridge forming element fulcrumed on the bar for vertical reciprocations, and means for reciprocating said ridge forming element a greater distance than the up and down movements of the feed dog.

22. In a feeding mechanism for sewing machines, the combination of a horizontal 4-motion feed dog, and means for imparting back and forth movements to said dog
5 including a rotary shaft, a feed rocker actuated from said shaft, and a feed bar pivotally connected to the rocker and supporting the feed dog, and means for imparting up and down movements to the feed dog comprising a frame pivoted to the feed rocker and extending under the feed bar, a spring interposed between the frame and the feed bar, a block slidably mounted in the frame, and an eccentric fixed to the shaft and engaging the block to slide the latter relative to the frame.
